UNITED STATES PATENT OFFICE.

JOHN A. DOBLE, OF SAN FRANCISCO, CALIFORNIA, ASSIGNOR TO DOBLE LABORATORIES, OF SAN FRANCISCO, CALIFORNIA, A CORPORATION OF CALIFORNIA.

STEAM-BOILER.

1,373,177.

Specification of Letters Patent. Patented Mar. 29, 1921.

Application filed May 22, 1918. Serial No. 235,950.

To all whom it may concern:

Be it known that I, JOHN A. DOBLE, a citizen of the United States, and a resident of the city and county of San Francisco 5 and State of California, have invented a certain new and useful Steam-Boiler, of which the following is a specification.

My invention relates to tubular steam boilers and more particularly to that type 10 commonly known as "semi-flash boilers".

An object of the invention is to provide a boiler of the character mentioned in which the heat issuing from the burner enters the boiler at the saturated steam zone and travels 15 elss through the boiler in the opposite direction to the water.

Another object of the invention is to provide a steam boiler of the character mentioned which provides a large steam liberating 20 surface.

A further object of the invention is to provide a steam boiler of the character mentioned in which the hot gases are caused to travel in a tortuous path around the tubes 25 in the boiler.

The invention possesses other advantageous features, some of which, with the foregoing, will be set forth at length in the following description where I shall outline 30 in full, that form of the invention which I have selected for illustration in the drawings accompanying and forming part of the present specification. In said drawings I have shown one specific form of the boiler 35 of my invention, but it is to be understood that I do not limit myself to such form, since the invention, as expressed in the claims may be embodied in a plurality of forms.

Referring to said drawings:

Figure 1 is a vertical section through the boiler of my invention.

Fig. 2 is a plan view of the water tanks.

Fig. 3 is a front elevation of the water 45 tanks.

Fig. 4 is a cross section on an enlarged scale taken on the line 4—4 Fig. 2.

The boiler of my invention is of the series tube type, that is, a boiler having a single 50 water tube, bent into convolutions, so that the water travels in a long circuitous path through the boiler. The tube 3 is arranged in a plurality of superposed horizontal grids, the successive convolutions of each 55 grid lying parallel to each other and par-

allel to the diameter of the inclosing heat insulating shell or casing 4. The corresponding convolutions of two contiguous grids are offset laterally with respect to each other so that the parallel tubes 5 in one 60 grid are staggered with relation to the parallel tubes in the grids next above and below. By this arrangement, the entire interior of the shell is filled with closely spaced parallel tubes which are successively offset 65 laterally with relation to each other, so that the gases of combustion pass in circuitous paths downwardly through the grids of tubes. The grids are connected together in series, forming in effect, a single tube. 70

Adjacent the upper end of the shell, the tube is connected to a series of superposed arc-shaped tanks 6 connected together in series and inclosing an open space which is the combustion chamber for the fuel mixture. Steam is liberated in these tanks and passes into the superheater tube 7 arranged above the tanks in one or more grids. Superheated steam is discharged from the 75 boiler through the pipe 8. 80

The burner 9 is arranged to discharge a flame into the boiler at the saturated steam zone or into the space surrounded by the saturated steam tanks 6, and the products of combustion pass downwardly through 85 the grids of water containing tubes and are discharged through the vent 12 at the bottom of the boiler. Water is introduced into the tube at the lower end and travels upwardly, in the opposite direction to the products of combustion, thereby insuring a maximum transfer of heat from the gases to the water. By introducing the fire at the saturated steam zone, the maximum amount of steam is liberated from the hot water which 90 is heated as it ascends through the tube and this steam is superheated in the tube 7 before it discharges from the boiler. This 95 boiler is particularly advantageous for steam automobiles, because the series tube arrangement and the introduction of the fire at the saturated steam zone, causes the very rapid generation of steam from an all cold condition, thereby permitting the automobile to be driven in a very short time after the fire 100 is started.

Means are provided for keeping the tanks 6, partly filled with water, so that a large steam liberating surface is provided. These tanks are horizontally disposed and are con- 110

nected together in series so that the water flows from one tank to the other. The adjacent ends of two successive tanks are connected together by a block 14 having a passage 15 therein, which opens upwardly on the face of a shoulder extending into the tank. Water must rise in the tank to the level of the shoulder before it passes to the tank next above and when it rises above this level it is discharged into the next upper tank. This keeps the level of the water in the tanks at substantially the level of the shoulders.

The boiler includes three zones, the water heating zone, the steam liberating or saturated steam zone and the steam superheating zone. The fire enters the boiler from the blower burner at the saturated steam zone and passes downward through the water heating zone in the opposite direction to the water therein. The burner 9 is of the rotary type and produces a mixture of liquid hydrocarbon fuel and air which is ignited and blown into the saturated steam zone in the boiler.

In the specification, I have described the tubular grids as being formed of parallel tubes arranged parallel to the diameter of the casing, but it is to be understood that the tube or tubes forming each grid may be disposed in any desirable manner either circumferentially, spirally or otherwise.

I claim:

1. In a boiler, a series of connected tubular grids arranged one above the other so that water passes upwardly through the grids successively, a series of tanks arranged above and connected to the series of grids and inclosing a combustion chamber, superheater tubes connected to the tanks and dis-

posed above the combustion chamber and means for introducing a flame into the combustion chamber and directing the heat thereof downwardly through said grids.

2. In a boiler, a series of connected tubular grids arranged one above the other so that water passes upwardly through the grids successively, a series of connected horizontal arc-shaped tanks arranged above and connected to said series of grids, means for maintaining said tanks partially filled with water, superheater tubes arranged above and connected to said tanks, means for introducing a flame into the space inclosed by said tanks and an outlet for the products of combustion at the bottom of the boiler.

3. In a boiler, a water tube through which water passes upwardly, a series of tanks arranged above and connected to said water tube, superheater tubes connected to and arranged above the tanks, and means for introducing a flame into the boiler at the zone of the tanks.

4. A boiler comprising a casing, a series of connected horizontal tubular grids therein arranged one above the other so that water passes upward through said grids successively, a series of connected tanks arranged above and connected to said grids, a horizontal tubular grid arranged above and connected to the upper of said series of tanks, and means for introducing a flame into the space inclosed by the tanks.

In testimony whereof, I have hereunto set my hand at San Francisco, California, this 16th day of May, 1918.

JOHN A. DOBLE.

In presence of—
H. G. PROST.
